UNITED STATES PATENT OFFICE.

WILLIAM L. KOHLER, OF MOUNT CLEMENS, MICHIGAN.

SHOE-TREE.

No. 926,750.

Specification of Letters Patent.

Patented July 6, 1909.

Application filed January 14, 1909. Serial No. 472,191.

To all whom it may concern:

Be it known that I, WILLIAM L. KOHLER, a citizen of the United States, residing at Mount Clemens, in the county of Macomb, and State of Michigan, have invented certain new and useful Improvements in Shoe-Trees, of which the following is a specification.

This invention relates to an improved shoe tree or form and its object is to provide a light, cheap, and durable device for the purpose which is so constructed that it may be quickly and easily adjusted to vary its width or length to fit shoes of different sizes; and further its construction is such as to provide a free circulation of air to dry the shoe when it is in place therein.

A further object of this invention is to provide the body of the form with adjustable means for stretching the shoe upper at a particular point where it is desired to relieve the pressure of the same upon that particular portion of the foot of the wearer and it is also an object of the invention to provide certain other new and useful features in the construction, arrangement, and combination of parts all as hereinafter more fully described reference being had to the accompanying drawings, in which,

Figure 1 is a perspective view of a device embodying this invention. Fig. 2 a longitudinal section of the same. Fig. 3 a transverse section on the line $x-x$ of Fig. 2. Fig. 4 a similar section on the line $y-y$ of Fig. 2. Fig. 5 is an enlarged sectional detail showing the stretcher in place upon the form.

The body of the device is preferably made of thin metal which is stamped, cast, or otherwise formed into the proper shape to fit the inside of a shoe and is made of three parts, the toe portion of the body of the form being divided longitudinally into two halves 1 and 2, the edges of which overlap at 3 along the center line of the upper side of the form and these overlapped edges are secured together by pins 4 in the edge of one-half of the form extending through transverse slots 5 in the edge of the other half of the form, so that the two edges are held together and at the same time the two halves 50 may be adjusted toward or from each other to vary the width of the toe form.

The parts 1 and 2 of the form are made of thin metal which is cut away or formed with any desired shape of openings to form 55 a skeleton frame or support for the shoe upper and permit the air to circulate freely

within the shoe to dry the upper, the dampness from which is carried through the openings in the form. The two parts of the body are formed along their lower edge with an inwardly extending flange 6 to engage and rest upon the insole of a shoe adjacent to the angle formed by the meeting of the insole and upper, the bottom of the form being otherwise entirely open so that the air has free access to the insole to dry the same thoroughly.

An ear 7 extends rearwardly from each side of the parts 1 and 2 of the form and to the rear end of these ears is pivotally attached the heel portion 8 of the form. This heel portion is also preferably made of thin metal with an inwardly extending flange 9 at its lower edge to engage the insole of the shoe, and with an upwardly extending portion 10 to engage the shoe upper above the heel counter. The heel portion is pivotally attached to the ears 7 by means of short bolts 11 carried by the ears, passing through longitudinal slots 12 in the forwardly projecting ends of the heel portion so that said heel portion may be turned freely upon the bolts and at the same time adjusted longitudinally thereon to vary the over-all length of the form.

The form is held in the shoe and its toe portion forced into the shoe to stretch the upper and hold it in shape, by means of a lever 13 pivoted intermediate its ends upon the transverse rod 14 mounted in the heel portion of the form. To the forward end of the lever 13 is pivoted a rack bar 15 having teeth or notches 16 to engage a transverse rod 17 carried by the toe portion of the form. The rack bar 15 is formed with a guard 18 embracing the rod 17 so that the rack bar may not be disengaged from the rod, but this guard 18 is placed at such a distance from the ends of the teeth that the bar may be lifted to disengage the teeth from the rod and permit of the free adjustment of the bar upon the rod. When the form is inserted within the shoe the lever 13 is thrown forward, and after the heel portion of the last has been adjusted longitudinally into engagement with the shoe counter with one of the teeth of the rack in engagement with the rod 17 the lever 13 is turned by means of its handle 19 into the position shown in full lines in Fig. 2. This movement of the lever forces the heel and toe portions of the form in opposite directions and brings the toe

portion into firm contact with the shoe upper. The handle portion 19 of the lever 13 is so made that when it is turned into engagement with the back of the heel portion 5 of the form the pivotal connection of the lever 13 to the bar 15 will be above a line drawn through the axis of the rod 17 and the pivot of the lever 13 and the lever and bar are thus locked in that position.

- 10 The two halves of the toe portion of the form are adjusted to vary the width of the form and held in their adjusted position by means of the rod 17 and a similar rod 20 extending across the form near the toe end. 15 These rods are provided with a right and left hand screw thread at their opposite ends to engage screw threaded openings in bosses 21 on the sides of the form, and thus by turning the rods the halves of the form are drawn 20 toward each other or spread apart according to the direction in which the rods are turned.

It is often found desirable to stretch the shoe upper at some particular point to relieve the pressure, as upon a corn or bunion, 25 and for this purpose a longitudinal slot 22 is formed in the side of the body at a point where these afflictions most commonly appear on the foot, as upon the outer side of the little toe or upon the toe joint, and in 30 this slot is adjustably secured a sleeve 23 which is internally screw threaded to receive the screw threaded shank 24 having upon its upper end a head or button 25 to engage the inner surface of the shoe upper and press the same outward. The sleeve 23 is formed with 35 a flange on its outer end to engage the outer side of the body and its inner end is screw threaded to receive a nut 26 to engage the inner side of the body and clamp the same 40 to hold the sleeve in place. By loosening the nut 26 the sleeve may be adjusted along the slot 22 to bring the button or head 25 to the exact point where it is desired to stretch the shoe upper. After the shoe form is in 45 place within the shoe and the head 25 adjusted to the proper position, this head may be moved outward to stretch the upper the desired amount by engaging a suitable tool with the inner end of the stem 24 and turning 50 the stem to project the head farther from the side of the shoe form. The slots 22 may be provided in the body wherever it is thought desirable and one or more of the stretcher devices may be used, or these devices 55 may be easily disengaged from the body and removed if they are not required.

Having thus fully described my invention what I claim is:

1. A shoe tree comprising a toe portion 0 formed of thin metal and provided with openings in its upper side to form a skeleton

body, ears extending rearwardly from the sides of said toe portion, a heel portion formed of thin metal and having longitudinal slots in its forwardly extending side portions, bolts carried by the ears and engaging the slots to pivotally connect the heel and toe portions, and means for adjusting the heel and toe portions one relative to the other.

65

2. A shoe tree comprising a toe portion and a heel portion pivotally united and adapted to be moved relatively in the direction longitudinally of the form, a lever pivotally supported by the heel portion, a rack 75 bar pivotally attached to one end of said lever and provided with a series of teeth, and a member carried by the toe portion adapted to be engaged by the teeth of the rack bar.

70

3. A shoe tree comprising a toe portion 80 and a heel portion pivotally united and adapted to be moved longitudinally one with relation to the other, a lever pivotally supported intermediate its ends upon the heel portion and adapted to engage at one end 85 the end of the heel portion, a rack bar pivotally attached to the other end of said lever and provided with teeth, and a transverse member carried by the toe portion adapted to be engaged by said teeth, said 90 transverse member and the pivot of the lever being so positioned relative to the end of the heel portion that when said lever is turned with its end engaging the end of the heel portion its opposite end will be above the plane 95 of said pivot and transverse member to lock the lever in position.

95

4. In a shoe tree the combination with a hollow body portion having a slot, a member having a head, a shank on said head extending inward through the slot, a sleeve on the shank having a screw threaded engagement therewith, and means for adjustably securing the sleeve in the slot.

100

5. In a shoe tree the combination of a hollow toe portion, a hollow heel portion pivotally attached to the toe portion and adapted to be moved longitudinally relative to the toe portion, a lever pivoted to the heel portion having an upwardly extending end 110 forming a handle adapted to engage the end of the heel, a bar pivoted to the opposite end of said lever and adapted to adjustably engage the toe portion and turn thereon when the lever is turned.

105

In testimony whereof I affix my signature in presence of two witnesses.

WILLIAM L. KOHLER.
